[57] CLAIM

The ornamental design for a combined tractor and trailing implement for supporting a crop header, as shown and described.

DESCRIPTION

FIG. 1 is a top plan view of a combined tractor and trailing implement for supporting a crop header showing our new design;

FIG. 2 is a left rear perspective view thereof;

FIG. 3 is an elevational view showing one side thereof;

FIG. 4 is an elevational view showing the opposite side thereof; and

FIG. 5 is a front elevational view thereof.

The broken lines in the drawings are for illustrative purposes only.
